RESPIRATOR

**Thomas A. Conley, Harrisville, R. I., assignor to
American Optical Company, Southbridge,
Mass., a voluntary association of Massachusetts**

Application December 24, 1948, Serial No. 67,180

15 Claims. (Cl. 128—141)

11

This invention relates to respirators and has particular reference to improved respirators of a type for attachment over the nose and mouth of an individual for filtering particulate or gaseous contaminants from air to purify it for breathing.

An object of this invention is to provide a respirator embodying a face piece molded of rubber or similar flexible material having the contour edge portions thereof which contact the face of the wearer turned inwardly so as to provide a comfortable snug fit against the face preventing leakage at contacting surfaces, the edge portions engaging the bridge of the nose and the chin being formed substantially flat to parallel the facial features, thus providing better contact and giving more comfort to the wearer, the face piece also embodying a flexible bracket attached to the inner surface thereof, which bracket provides for easier adjustment of the face piece to the face of the wearer and retains the face piece in desired adjusted shape, such a face piece being easily and efficiently adapted to faces of varying lengths.

Another principal object of the invention is to provide improved inhalation and exhalation valve constructions, said valves being recessed to avoid interference caused by contacting the wearer's face or clothing during the process of breathing, the face piece of the respirator embodying portions of thickened area around the inhalation and exhalation parts permitting the valves to be recessed without the necessity of providing separate guards to protect the valves.

Another object is to provide a respirator of the above character with an improved inhalation valve construction to minimize the resistance due to the sticking of a flexible valve member to a flat member contacted thereby, and embodying a valve seat having a circular knife-edge rim adapted to be engaged by the flexible valve member which is suspended upon a pin member supported by the valve seat, the pin member also having a portion extending toward the filter to prevent filters of the non-rigid type from excessive sagging and possibly plugging the valve opening.

Another object is to provide improved means for attaching to respirators filters of either the flat disc type, such as impregnated paper, felt, or the like, or of the filled cartridge type containing such filtering media as charcoal, silica gel, or the like, the means embodying a clamp ring disposed over the peripheral edge of the filter and engaging the peripheral edge portion of the

cover, the clamp ring being adapted to be screwed onto the holding device therefor without necessitating rotation of the cover with possible consequent damage to or unseating of the filter resulting in leakage of unfiltered air.

Another object is to provide a respirator of the above character having a flexible metal brace for providing easy adjustment of the face piece to the face of the wearer and retention of the face piece in adjusted position, with the head band supporting the device on the wearer's face being so connected that the pull thereon is directed to the metal brace rather than to the pliable material of the face piece.

15 Another object of the invention is to provide a compact and light weight respirator of the above character in which the filter elements are easily removed and replaced and in which the construction of parts is such that they provide unusually low resistance to breathing.

Other objects and advantages of the invention will become apparent from the following description taken in connection with the accompanying drawings, in which:

Fig. 1 is a front elevational view of a respirator embodying the invention:

Fig. 2 is a sectional view taken on line 2-2 of Fig. 1 and showing particularly the improved method of shaping the edge portions of the face piece for engagement with the face of the wearer.

Fig. 3 is a rear elevational view of the device illustrated in Fig. 1:

Fig. 4 is a fragmentary sectional view taken on line 4—4 of Fig. 1; and

Fig. 5 is a fragmentary front elevational view of a portion of the face piece adjacent the filter means showing the construction of the face piece in this area.

piece in this area.

In the manufacture and use of respirators of the type embodying the present invention, comfort and efficiency are the most important features to be considered. Therefore, the present device is particularly constructed so that it will be comfortably supported upon the face of the wearer with the contour edges of the face piece being shaped for increased surface engagement with the face and with flexible reinforcing means being provided on the inner surface of the face piece for adjusting the face piece to fit more comfortably on the wearer's face and retaining it in adjusted position.

Respirators should also be provided with efficient inhalation and exhalation valves constructed so as to provide greater ease of breathing with less possibility of inefficiency caused by clogging.

sticking or otherwise poorly working parts, which condition adds to the resistance to breathing. The present invention overcomes many of these objections by providing inhalation and exhalation valves having an improved construction and which are recessed so that the operative parts of the valves will not engage surfaces or objects which may cause consequent interference with the operation thereof.

Referring more particularly to the drawings wherein like characters of reference designate like parts throughout the several views, the respirator embodying the invention comprises a face piece 6 adapted to cover the lower portions of the face of a wearer and cushioned under the wearer's chin, the face piece 6 being formed of flexible material such as soft rubber or the like which can readily adapt itself to the contour of the facial features of the wearer so as to prevent passage of air between the edges of the face piece and the wearer's face. The face piece 6 is provided with an inturned lip 7 throughout its entire contour edge, which lip 7 may be substantially decreased in thickness from the major portion of the face piece to provide greater flexibility thereof and to insure an efficient seal between the face piece and the wearer's face with maximum comfort to the wearer, and in the present construction is formed as a rounded lip about a major portion of the contour edge of the face piece, and as a flat lip adjacent the chin and nose bridge portions thus being formed substantially parallel to these features.

In accordance with the invention, air, as it passes into the face piece 6 upon inhalation by the wearer, is filtered by a suitable filter 8 (Fig. 4) which filter may be of either the flat disc or the filled cartridge type possessing the desired filtering and air resistance characteristics. The illustrated embodiment of the invention shows a pair of filter elements disposed symmetrically one on each side of the face piece and in spaced opposed relationship on the outer surface thereof out of the line of vision of the wearer. In addition to being out of the useful field of vision of the wearer, this construction provides equal weight or balance to each side of the respirator, thereby decreasing strain on the face piece, which sometimes exists when the filtering element is disposed centrally of the face piece, and adding to the comfort of the wearer.

A feature of the invention resides in the provision of particularly advantageous means for supporting a filter such as a felt filter 8 while positively sealing it against leakage of air around its edge. Each of the filter units includes a cylindrical casing comprising a circular ring-like base 9, a cover 10, and a retaining or clamping ring 11, all of which are adapted to be positioned as a unit over and externally of an opening 12 communicating with the interior of the face piece, the face piece being formed substantially thick adjacent the openings 12. The opening 12 (Fig. 5) is provided with a flat circular edge portion 13 therearound, which portion has a pair of diametrically opposed recesses 14 formed in the edge thereof in which are adapted to reside a pair of flange extensions 15 (Fig. 4) formed on the inner edge of the base 9 and in diametrical opposition to each other. The base 9 is held firmly over the opening 12 by a grommet 16, the outer edge portion of the grommet 16 extending over the inner edge portion 18 of the base 9 holding the base firmly against the portion 13, with the ex-

tensions 15 within the recesses 14 serving to prevent the base from rotating.

The base 9 is formed with a forwardly extending portion 19 having a portion 20 extending outwardly therefrom (Fig. 4) against which is adapted to reside a washer or gasket 21 of rubber, fibre or other resilient material, the portion 20 in turn having a forwardly extending portion 22 extending therefrom, the portion 22 being provided with threads on its outer surface. The disc-like filter 8 is positioned with its peripheral rear edge portion engaging the gasket 21, and the cover 10 is placed over the filter to retain it in place. The cover 10 is provided with a 15 perforated front surface 23 and a side surface 24, the side surface 24 being provided with a plurality of knobs or raised areas 25 adjacent the front surface 23 and with an outwardly extending flanged portion 26 adjacent its rear edge, the flanged portion 26 engaging the filter 8. The retaining ring 11 is provided to retain the cover 10 and base 9 in assembled relation and is formed substantially U-shape in section (Fig. 4) with its inner portion 27 being of a size to normally reside between the knobs 25 and flange 26 of the cover 10. The opposed outer portion 28 of the ring 11 is adapted to extend rearwardly over the portion 22 of the base 9 and is provided with threads on its inner surface for engaging the threads on the portion 22. When the ring 11 is threaded onto the base 9, which rotary movement can be accomplished easily due to the raised areas 29 formed thereon, the edge of the ring portion 27 is brought to bear upon the flange 26 of the cover 10, pressing the flange against the filter 8. Thus, the complete unit is sealed against leakage and unfiltered air permitted to enter the assembly only through the openings 30 provided therefor in the perforated front surface 23 of the cover 10.

This means enables the cover to be readily removed for easily changing filters when desired, the flange 26 provides a bearing surface for the edge of the ring portion 27 during the rotation thereof and enables the assembling of the filter unit without cutting, fraying or otherwise damaging the filter or unseating the edge of the filter from its position against the gasket which might occur as by turning a sharp or narrow edge surface in direct engagement with the fibrous surface of a filter.

To prevent collapse of the face piece 6 and to permit adjustment of the face piece to fit the facial contours of the wearer there is provided a 55 flexible metal reinforcing member 31 (Fig. 3) positioned inside the face pieces 6, the member 31 having circular ring-like end portions 32 connected by a strap portion 33, the end portions 32 being positioned over the inhalation openings 60 12 and held in place by the inner ends of the grommets 16. The face piece 6 and reinforcing member 31, both being flexible, are easily bent and shaped so that the face piece can be adjusted to fit the wearer's face and will, through the inherent characteristic of the member 31, retain their adjusted positions.

A circular valve seat is adapted to be carried by each grommet 16, each valve seat being press fit into the inner chamber of the grommet and 70 shaped as a circular ring-like member having a perforated disc-shaped inner surface 34 directed toward the wearer's face and having an outwardly extending peripheral flange 35 formed on its rear edge in engagement with the rear end of 75 the grommet for limiting the forward movement

of the seat 36 during assembly and thus positioning the seat 36 so that the surface of a movable valve member 37 associated therewith will be positioned below the level of the inner surface of the face piece 6 (Fig. 4). The valve member 37 is supported by a centrally disposed pin 38 which is carried by the valve seat 36, the pin being of sufficient length to extend toward the filter 8 sufficiently to prevent the filter from sagging toward the valve seat 36 and possibly plugging the opening 12. The valve member 37 is made of thin flexible material such as gum rubber or the like and operates in the conventional manner to permit ingress of filtered air into the interior of the face piece through the perforations in the surface 39 of the seat 36 and to prevent egress of exhaled air into the filter element. To properly seal the unit against the passage of exhaled air, the valve member 37 is adapted to seat upon a continuous substantially knife-edge rim 40 formed on the inner surface 39 of the valve seat 36 encircling the perforated area, thus preventing sticking of the valve to the seat which sometimes occurs when moisture exists in a construction embodying a flat surface adapted to be engaged by the valve. Since the face piece is formed substantially thick adjacent the openings 12 the valves can be recessed sufficiently to permit efficient functioning thereof without providing separate guards to protect the valves from interference such as may be encountered when the valve is contacted by the wearer's face.

Adjacent its lower end the face piece 6 is provided with an exhalation port 41 in which is secured a bracket 42 having spaced openings 43 therein. A movable exhalation valve member 44 is secured to the outer surface of the bracket 42 by means such as rivets 45 or the like and operates to cover the openings 43 during inhalation, preventing unfiltered air from entering the face piece, and opens the openings to the passage of air to be exhausted therethrough. The face piece is constructed so as to be of substantial thickness adjacent the port 41 so that the valve member 44 will, when assembled therein, be positioned substantially below the level of the outer surface of the face piece, thus preventing the valve member 44 from contacting the wearer's clothing or other objects with possible consequent interference with the operation of the valve member.

The respirator is provided with the usual head straps 46 for holding it on the face of the wearer. As shown in Fig. 3, the straps 46 are inserted through loops 47. The loops 47 are adapted to be connected to one of a plurality of pin members 48 located on the rear of the filter base 9. Thus, by connecting loops 47 to the desired pin members 48 the straps 46 can be adjusted to provide additional comfort of the respirator on the face of the wearer. By attaching the straps 46 to the filter bases 9 the pull exerted by the head band will be transmitted to the metal reinforcing member 31 rather than to the pliable material from which the face piece is made.

It is to be understood that if desired a filter of the cartridge or canister type can be attached to the base 9 in a manner similar to the cover 8, as shown by dot and dash lines in Fig. 4. The actual filter media used with the present respirator, however, can be greatly varied to adapt the respirator for use to filter either solid or gaseous particles.

From the foregoing it will be seen that the present invention embodies a respirator having

improved means for easily and efficiently attaching a filter or filters to the face piece, improved inhalation and exhalation valve constructions, and improved means for shaping the respirator face piece to the face of the wearer, all of which improved features result in a respirator made to be worn more comfortably on the face of the wearer.

While certain novel features of the invention have been shown and described and are pointed out in the annexed claims, it will be apparent that various omissions, substitutions and changes in the formation and details of the device illustrated and in its use may be made by those skilled in the art without departing from the spirit of the invention.

I claim:

1. A respirator comprising a flexible face piece shaped substantially to fit the face of a wearer and having substantially thin flat inturned portions throughout its contour edge for engagement with the wearer's face, a pair of filter carrying bases disposed in spaced relation one on either side of the outer surface of the face piece, each being located over a port communicating with the interior of the face piece, grommets mounted within said ports and securing said bases to the face piece, an exhalation valve disposed in the lower frontal region of the face piece, and reinforcing means for the face piece comprising a flexible member having end portions disposed over the inner ends of said ports and secured thereover by said grommets and a connecting portion between said end portions, said member being characterized by its ability to be adjusted with the face piece in adjusting the face piece to the face of the wearer and to retain the face piece in adjusted position.

2. A respirator comprising a flexible face piece shaped substantially to fit the face of a wearer and having substantially thin flat inturned portions throughout its contour edge for engagement with the wearer's face, a pair of filter carrying bases disposed in spaced relation one on either side of the outer surface of the face piece, each being located over a port communicating with the interior of the face piece, grommets mounted within said ports and securing said bases to the face piece, an exhalation valve disposed in the lower frontal region of the face piece, and reinforcing means for the face piece comprising a flexible member having ring-like end portions disposed over the inner ends of said ports and secured thereover by said grommets and a substantially thin narrow strap connecting said end portions, said member being characterized by its ability to be adjusted with the face piece in adjusting the face piece to the face of the wearer and to retain the face piece in adjusted position.

3. A respirator comprising a flexible face piece shaped substantially to fit the face of a wearer and having substantially thin flat inturned portions throughout its contour edge for engagement with the wearer's face, a pair of filter units disposed in spaced relation one on either side of the outer surface of the face piece, each filter unit being located over a port communicating with the interior of the face piece and comprising a ring-like base positioned in engagement with the outer surface of the face piece, a disc-like filter positioned within said base, a foraminous cover disposed over the outer surface of the filter and having a circular edge portion contacting the outer peripheral edge portion of the filter, and a retaining ring mounted over the peripheries of said base and cover and adapted to urge said

cover toward said base to hold the filter securely in position, grommets mounted within said ports and securing said bases to the face piece, and an exhalation valve disposed in the lower frontal region of the face piece.

4. A respirator comprising a flexible face piece shaped substantially to fit the face of a wearer and having substantially thin flat inturned portions throughout its contour edge for engagement with the wearer's face, a pair of filter units disposed in spaced relation one on either side of the outer surface of the face piece, each filter unit being located over a port communicating with the interior of the face piece and comprising a ring-like base positioned in engagement with the outer surface of the face piece and having at least one projection formed thereon extending towards the face piece and adapted to reside within at least one recess provided therefor in the surface of the face piece for preventing rotation of the base, a disc-like filter positioned within said base, a foraminous cover disposed over the outer surface of the filter and having a circular edge portion contacting the outer peripheral edge portion of the filter, and a retaining ring mounted over the peripheries of said base and cover and adapted to urge said cover toward said base to hold the filter securely in position, grommets mounted within said ports and securing said bases to the face piece, and an exhalation valve disposed in the lower frontal region of the face piece.

5. A respirator comprising a flexible face piece shaped substantially to fit the face of a wearer and having substantially thin flat inturned portions throughout its contour edge for engagement with the wearer's face, a pair of filter units disposed in spaced relation one on either side of the outer surface of the face piece, each filter unit being located over a port communicating with the interior of the face piece and comprising a ring-like base positioned in engagement with the outer surface of the face piece and having a threaded portion extending in a direction away from the face piece, a disc-like filter positioned within said base and having its inner peripheral edge portion engaging said base, a foraminous cover disposed over the outer surface of the filter and having a circular edge portion contacting the outer peripheral edge portion of the filter, and a retaining ring threadedly mounted on the threaded portion of said base and adapted to urge said cover toward said base to hold the filter securely in position, grommets mounted within said ports and securing said bases to the face piece, and an exhalation valve disposed in the lower frontal region of the face piece.

6. A respirator comprising a flexible face piece shaped substantially to fit the face of a wearer and having substantially thin flat inturned portions throughout its contour edge for engagement with the wearer's face, a pair of filter units disposed in spaced relation one on either side of the outer surface of the face piece, each filter unit being located over a port communicating with the interior of the face piece and comprising a ring-like base positioned in engagement with the outer surface of the face piece and having a threaded portion extending in a direction away from the face piece, a ring-like gasket mounted within said base and in abutment therewith throughout its entire inner peripheral edge, a disc-like filter positioned within said base and having its inner peripheral edge portion engaging said gasket, a foraminous cover disposed over the outer surface of the filter and having a circular edge portion

contacting the outer peripheral edge portion of the filter, and a retaining ring threadedly mounted on the threaded portion of said base and adapted to urge said cover toward said base to hold the filter securely in position, grommets mounted within said ports and securing said bases to the face piece, and an exhalation valve disposed in the lower frontal region of the face piece.

7. A respirator comprising a flexible face piece shaped substantially to fit the face of a wearer and having substantially thin flat inturned portions throughout its contour edge for engagement with the wearer's face, a pair of filter carrying bases disposed in spaced relation one on either side of the outer surface of the face piece, each being located over a port communicating with the interior of the face piece, grommets mounted within said ports and securing said bases to the face piece, a flutter valve unit disposed within each of said grommets and comprising a valve seat having a foraminous central portion and a knife-edge inwardly directed rim encircling said foraminous central portion and a flutter valve disposed over the inner surface of the valve seat in engagement with said knife-edge rim, the flutter valves being positioned within said grommets at a sufficient depth whereby they will be unable to engage the wearer's face, and an exhalation valve disposed in the lower frontal region of the face piece.

8. A respirator comprising a flexible face piece shaped substantially to fit the face of a wearer and having substantially thin flat inturned portions throughout its contour edge for engagement with the wearer's face, a pair of filter carrying bases disposed in spaced relation one on either side of the outer surface of the face piece, each being located over a port communicating with the interior of the face piece, grommets mounted within said ports and securing said bases to the face piece, a flutter valve unit disposed within each of said grommets and comprising a valve seat having a foraminous central portion and a knife-edge inwardly directed rim encircling said foraminous central portion, a pin member centrally located in said foraminous central portion and having one end extending toward said filter and adapted to be engaged thereby to prevent the filter, when sagging, from plugging the port, and a flutter valve disposed over the inner surface of the valve seat in engagement with said knife-edge rim, and an exhalation valve disposed in the lower frontal region of the face piece.

9. A respirator comprising a flexible face piece shaped substantially to fit the face of a wearer and having substantially thin flat inturned portions throughout its contour edge for engagement with the wearer's face, a pair of filter carrying bases disposed in spaced relation one on either side of the outer surface of the face piece, each being located over a port communicating with the interior of the face piece, grommets mounted within said ports and securing said bases to the face piece, a flutter valve unit disposed within each of said grommets and comprising a valve seat having a foraminous central portion and a knife-edge inwardly directed rim encircling said foraminous central portion, a pin member centrally located in said foraminous central portion and having one end extending toward said filter and adapted to be engaged thereby to prevent the filter, when sagging, from plugging the port, and a flutter valve supported by the inner end of said pin member disposed over the inner surface of the valve seat in engagement with said knife-edge

rim, the flutter valves being positioned within said grommets at a sufficient depth whereby they will be unable to engage the wearer's face, and an exhalation valve disposed in the lower frontal region of the face piece.

10. A respirator comprising a flexible face piece shaped substantially to fit the face of a wearer and having substantially thin flat inturned portions throughout its contour edge for engagement with the wearer's face, a pair of filter carrying bases disposed in spaced relation one on either side of the outer surface of the face piece, each being located over a port communicating with the interior of the face piece, grommets mounted within said ports and securing said bases to the face piece, an exhalation valve unit disposed in the lower frontal region of the face piece and comprising a perforated bracket secured within an opening in the face piece and a flutter valve operatively secured to the outer surface of the bracket and covering the perforations therein, the exhalation valve unit being positioned within said opening at a sufficient depth whereby the flutter valve will be unable to engage objects positioned outside the opening, and reinforcing means for the face piece comprising a flexible member having end portions disposed over the inner ends of said ports and secured thereover by said grommets and a connecting portion between said end portions, said member being characterized by its ability to be adjusted with the face piece in adjusting the face piece to the face of the wearer and to retain the face piece in adjusted position.

11. A respirator comprising a flexible face piece shaped substantially to fit the face of a wearer and having substantially thin flat inturned portions throughout its contour edge for engagement with the wearer's face, a pair of filter units disposed in spaced relation one on either side of the outer surface of the face piece, each filter unit being located over a port communicating with the interior of the face piece and comprising a ring-like base positioned in engagement with the outer surface of the face piece and having at least one projection formed thereon extending towards the face piece and adapted to reside within at least one recess provided therefor in the surface of the face piece for preventing rotation of the base and having a threaded portion extended in a direction away from the face piece, a ring-like gasket mounted within said base and in abutment therewith throughout its entire inner peripheral edge, a disc-like filter positioned within said base and having its inner peripheral edge portion engaging said gasket, a foraminous cover disposed over the outer surface of the filter and having a circular edge portion contacting the outer peripheral edge portion of the filter and a retaining ring located over the peripheries of said base and cover and threadedly mounted on the threaded portion of said base and adapted to urge said cover toward said base to hold the filter securely in position, grommets mounted within said ports and securing said bases to the face piece, a flutter valve unit disposed within each of said grommets and comprising a valve seat having a foraminous central portion, an inwardly directed knife-edge rim encircling said foraminous central portion, a pin member centrally located in said foraminous central portion and having one end extending toward said filter and adapted to be engaged thereby to prevent the filter, when sagging, from plugging the port, and a flutter valve supported by the inner end of said

pin member and disposed over the inner surface of the valve seat in engagement with said knife-edge rim, the flutter valve units being positioned within said grommets at a sufficient depth whereby the flutter valves will be unable to engage the wearer's face, an exhalation valve unit disposed in the lower frontal region of the face piece and comprising a perforated bracket secured within an opening in the face piece and a flutter valve operatively secured to the outer surface of the bracket and covering the perforations therein, the exhalation valve unit being positioned within said opening at a sufficient depth whereby the flutter valve will be unable to engage objects positioned outside the opening, and reinforcing means for the face piece comprising a flexible member having ring-like end portions disposed over the inner ends of said ports and securely held thereover by the inner ends of said grommets and a substantially thin narrow strap connecting said end portions, said member being characterized by its ability to be adjusted with the face piece in adjusting the face piece to the face of the wearer and to retain the face piece in adjusted position.

12. A respirator comprising a face piece shaped to overlie the nose and to fit the face of the wearer, said face piece having an opening therein, a connection member secured to the face piece and having an opening therein in alignment with the opening in said face piece and an intermediate shoulder portion and an attachment portion, a filter member having its contour edges overlying the shoulder portion and lying within the attachment portion, a cap-like member having a peripheral flange overlying said filter with the flange engaging that portion of the contour of the filter overlying the shoulder portion and a connection ring member having an inwardly turned portion engaging the flange of the cap-like member and having an attachment portion in connected relation with the attachment portion of the main connection means.

13. A respirator comprising a face piece shaped to overlie the nose and to fit the face of the wearer, said face piece having an opening therein, a connection member secured to the face piece and having an opening therein in alignment with the opening in said face piece and an intermediate shoulder portion and an attachment portion, a filter member having its contour edges overlying the shoulder portion and lying within the attachment portion, a cap-like member having a peripheral flange overlying said filter with the flange engaging that portion of the contour of the filter overlying the shoulder portion and a connection ring member having an inwardly turned portion engaging the flange of the cap-like member and having an attachment portion in connected relation with the attachment portion of the main connection means, said cap-like member having a plurality of openings therein.

14. A respirator comprising a face piece shaped to overlie the nose and to engage the face of the wearer, said face piece having an opening therein, a connection member attached to said face piece and having an opening in alignment with the opening in the face piece and further having an engagement portion extending in a sidewise direction and an attachment portion extending forwardly of said engagement portion, a filter member having its contour portion overlying the engagement portion, a perforated cap-like member having a peripheral flange overlying that portion of the filter which overlies the engagement portion and an annular member having an edge

2,505,173

11

portion engagement with the peripheral flange of the cap and having an attachment portion in connected relation with the attachment portion of the main connection means.

15. A respirator comprising a face piece shaped to overlie the nose and to engage the face of the wearer, said face piece having an opening therein, a connection member attached to said face piece and having an opening in alignment with the opening in the face piece and further having an engagement portion extending in a sidewise direction and an attachment portion extending forwardly of said engagement portion, a filter member having its contour portion overlying the

12

engagement portion, a perforated cap-like member having a peripheral flange overlying that portion of the filter which overlies the engagement portion and an annular member having an edge portion engagement with the peripheral flange of the cap and having an attachment portion in connected relation with the attachment portion of the main connection means, said filter member and engagement portion having a resilient sealing ring therebetween.
